UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

REINFORCED CONCRETE STRUCTURE.

No. 891,929.

Specification of Letters Patent. Patented June 30, 1908.

Application filed October 17, 1907. Serial No. 397,849.

To all whom it may concern:

Be it known that I, GEORGE M. GRAHAM, a citizen of the United States of America, and a resident of Chicago, in the county of Cook and State of Illinois, have invented certain new and useful improvements in Reinforced Concrete Structures, of which the following is a specification.

This invention relates to structural iron columns forming parts of the skeleton reinforcing frame of concrete buildings; and the present improvement has for its object to provide a simple, light and substantial structural arrangement and combination of parts adapted to afford a ready and firm support for the series of tubes which in turn afford support for the reinforcing wire webs of the walls, floors and other parts of a reinforced concrete building, all as will hereinafter more fully appear.

In the accompanying drawings:—Figure 1, is a side elevation of a portion of a column, embodying the present improvement and having portions of the tubular girders in place. Fig. 2, is a horizontal section on line $x-x$, Fig. 1. Fig. 3, is a similar view on line $x'-x'$, Fig. 1. Fig. 4, is a view similar to Fig. 3, with the concrete mass and accessories in place.

Similar numerals of reference indicate like parts in the several views.

Referring to the drawings, 1 represents a series of four vertically arranged structural iron bars of an angle or other suitable shape in cross section, and which are held in separated relation by the diagonal bracing bars 2, as usual in built up structural iron columns.

3 are a series of U shaped stirrup pieces arranged between pairs of the column bars 1 and with their vertical portions secured to said bars 1 by rivets as shown. As so arranged, bearings having a semi-circular bottom, are provided for the series of tubular horizontal girders 4, which rest in said stirrups as shown, and are held in position by the transverse bolts 5, which extend through the webs of the bars 1, the vertical portions of the stirrups 3 and the axial portion of the circular girders 4, to afford a strong and rigid attachment of the parts.

6 are flanged pieces secured to the column bars 1 immediately beneath the stirrups 3, to provide additional support for the same under the load or stress imposed thereon in the completed structure.

7 is the mass of concrete, in which the column constructed as above described is embedded.

8 is the perforated sheet lathing which holds the concrete in place while setting, and to which the finishing outer coat of concrete or the like is applied, as usual in the construction of reinforced concrete columns of the present type.

Having thus fully described my said invention what I claim as new and desire to secure by Letters Patent, is:—

1. In a reinforcing frame for concrete structures, the combination of a series of vertical structural iron members, braces securing the same in separated relation, a series of U shaped stirrup pieces secured between said vertical members with their arms extending upwardly, and horizontal tubular frame members resting in said stirrup pieces.

2. In a reinforcing frame for concrete structures, the combination of a series of vertical structural iron members, braces securing the same in spaced rectangular relation, a series of U shaped stirrup pieces secured between said vertical members with their arms extending upwardly, and horizontal tubular frame members resting in said stirrup pieces.

3. In a reinforcing frame for concrete structures, the combination of a series of vertical structural iron members, braces securing the same in spaced rectangular relation, a series of U shaped stirrup pieces secured between said vertical members with their arms extending upwardly, horizontal tubular frame members resting in said stirrup pieces, and transverse bolts passing through the vertical members, stirrup pieces and tubular members to secure the parts in place.

4. In a reinforcing frame for concrete structures, the combination of a series of vertical structural iron members, braces securing the same in spaced rectangular relation, a series of U shaped stirrup pieces secured between said vertical members with their arms extending upwardly, horizontal tubular frame members resting in said stirrup pieces, and transverse bolts passing through the vertical members, stirrup pieces and tubular frame members to secure the parts in place.

5. In a reinforcing frame for concrete structures, the combination of a series of vertical structural iron members, braces securing the same in separated relation, a series of U shaped stirrup pieces secured between said

- vertical members with their arms extending upwardly, flanged pieces secured to said vertical members and located beneath and in contact with said stirrup pieces to provide 5 a support therefor, and horizontal tubular frame members resting in said stirrup pieces.
6. In a reinforcing frame for concrete structures, the combination of a series of vertical structural iron members, braces securing 10 the same in spaced rectangular relation, a series of **U** shaped stirrup pieces secured between said vertical members with their arms extending upwardly, flanged pieces secured to said vertical members and located beneath
- 15 and in contact with said stirrup pieces to provide a support therefor, and horizontal tubular frame members resting in said stirrup pieces.
7. In a reinforcing frame for concrete 20 structures, the combination of a series of vertical structural iron members, braces securing the same in separated relation, a series of **U** shaped stirrup pieces secured between said vertical members with their arms extending
- 25 upwardly, flanged pieces secured to said vertical members and located beneath and in

contact with said stirrup pieces to provide a support therefor, horizontal tubular frame members resting in said stirrup pieces, and transverse bolts passing through the vertical 30 members, stirrup pieces and tubular members to secure the parts in place.

8. In a reinforcing frame for concrete structures, the combination of a series of vertical structural iron members, braces securing 35 the same in spaced rectangular relation, a series of **U** shaped stirrup pieces secured between said vertical members with their arms extending upwardly, flanged pieces secured to said vertical members and located beneath 40 and in contact with said stirrup pieces to provide a support therefor, horizontal tubular frame members resting in said stirrup pieces, and transverse bolts passing through the vertical 45 members, stirrup pieces and tubular members to secure the parts in place.

Signed at Chicago, Illinois this 2nd day of October 1907.

GEORGE M. GRAHAM.
